UNITED STATES PATENT OFFICE.

PER WALFRID BRUNDIN, OF NEW YORK, N. Y., ASSIGNOR TO THE NEW YORK VENETIAN BLIND COMPANY, OF SAME PLACE.

VENETIAN BLIND.

SPECIFICATION forming part of Letters Patent No. 601,612, dated March 29, 1898.

Application filed December 28, 1896. Serial No. 617,198. (No model.)

To all whom it may concern:

Be it known that I, PER WALFRID BRUNDIN, a citizen of the United States, and a resident of New York city, in the county and 5 State of New York, have invented certain new and useful Improvements in Venetian Blinds, of which the following is a specification.

My invention consists of improvements in the construction of some of the parts of Venetian-blind apparatus whereby it is designed to provide simpler and more efficient apparatus for operating and controlling the blinds, as hereinafter described, reference being made to the accompanying drawings, in 15 which—

Figure 1 is a front elevation of parts of a Venetian blind constructed according to my invention, with a part in section; Fig. 2, an elevation in a view at right angles to that of 20 Fig. 1, also with a part in section. Fig. 3 is an elevation in a view in the opposite direction of that of Fig. 2. Fig. 4 is a detail, partly in front elevation and partly in longitudinal section, of the roller; and Fig. 5 is an end view 25 of the roller, side view of a pawl for locking it, and a section of a pawl for controlling the action of the locking-pawl. Fig. 6 is a detail, partly in front elevation and partly in section, showing a modified construction of apparatus for insuring release of the roller-holding pawls for letting the blind down. Fig. 7 is a section of Fig. 6 on line 2 2. 30

The slats *a* are suspended from a rocker-bar *b* by the straps *c*, as usual, but the rocker 35 is pivoted at *e*, concentrically in the hangers *d* instead of eccentrically, and a coiled spring *f* is arranged in the rocker and in connection with the non-rotatable pivot-rod *g* for normally turning the rocker to close the slats, as 40 represented in Fig. 1, but the use of the spring is alike applicable with the eccentrically-arranged rocker depending on the gravitating action of the heavy side for closing the slats which is sometimes employed.

The rocker *b* is provided at one end with a 45 crank *h* for opening the slats, as represented in Fig. 2, by means of a cord *i*, the crank being arranged at such an angle that by pulling the cord downward and fastening it on a 50 stud, button, clasp, or other fastener in a suitable position, or being held by a counter-

balance-weight, as *y*, the slats will be held open. Instead of arranging this pull-cord *i* to hang directly from the end of the crank and subjecting the operator to the labor of 55 contracting the spring by direct action I have connected it by a pulley-block *j*, connected by cord *j'* to the crank, with the pull-cord *i* connected to a hook *k* at the top of the window-frame and passed through said block, 60 and a guide *l* also at the top of the window-frame, whereby the operation is made easier, as will be well understood.

The usual roller *m*, slat-raising cord *n*, and pull-cord *o* are employed for raising the 65 slats, as shown in Fig. 2. Also one or more ratchet-notches *p* in the stationary pivot-hub *q* and pawls *s* on the end of the roller are employed for locking the roller and holding up the slats. 70

To facilitate the release of the locking-pawl when it is desirable to let the slats down it is customary to first pull the roller by a jerk on the cork *o* in the reverse direction to thrust out the pawl, so that when the pull on the 75 cork *o* is released the pawl will escape the notch and the slats will descend. It will be seen that to insure this operation when the slats are raised to the uppermost limit there must always be some slack space above the 80 position in which the uppermost slat comes to rest when the pawl locks the roller, for if the locking should occur coincidently with the contact of the upper slat with the rocker-bar the roller could not respond to the jerk 85 for throwing out the pawl. I have therefore provided means for insuring such slack which, as represented in Figs. 1, 2, 3, and 4, may consist of the weighted pass-over pawl *t* on the pivot *u* and in such relation to the notch *p* 90 that it will lodge therein, so that the pawls *s* will pass over it and a predetermined distance beyond the shoulder of the notch when the slats are being raised and then drop into the notch above said pass-over pawl and will 95 thrust it out of the notch and return to the shoulder of the notch for locking, thus insuring the requisite slack for enabling the locking-pawl to be jerked out of the notch.

Although the length of the cords *n* may be 100 so adjusted relatively to the pawls *s* on the roller and the pawl-engaging notch that such

slack may be provided for at first, the cords may vary so in length by hygroscopic action and other causes that there would be times when the releasing of the roller would be difficult without this provision.

The pass-over pawl may be constructed in various different ways provided it will lodge in the notch, so that pawls *s* will pass over it, and it will be displaced properly for locking the roller, as represented in Figs. 1 to 5, inclusive. It is provided with a stop *v*, which bears against the bracket to prevent the weight from thrusting the operative end up too high. In Figs. 6 and 7 this pass-over pawl is represented as an arm *a'* of a rod *b'*, resting in the notch *p'* of the hub *q*, said rod *b'* extending down along the bracket *d*, in which the roller *m* and the rocker-bar are pivoted and connected to the pivot *d'* of the rocker-bar in such manner that said rocker-bar being lifted by the slats when pulled up tightly against it, suitable slack being provided therefor in the pivot-holes *e*, arm *a'* will be elevated, so that a pawl *s*, that would without said arm engage the notch *p'* with insufficient slack for release, will be prevented from engaging at all, whereby the slats will drop, causing the arm to drop also, and the next pawl will drop in the notch and lock the roller, thus maintaining ample slack for release. Other contrivances may also be arranged for this purpose, and I do not limit myself to any particular device therefor.

I claim—

- 35 1. In a Venetian blind, the combination with the slats, slat-suspending straps, and the slat-raising roller, of the slat opening and closing rocker-bar and a spring for actuating said rocker-bar for closing the slats, said 40 rocker having the pull-cord for opening the slats substantially as described.
2. In a Venetian blind, the combination with the slats, slat-suspending straps, and the slat-raising roller, of the slat opening and 45 closing rocker-bar, spring for actuating the rocker-bar to close the slats, and a pull-cord for actuating the rocker-bar to open the slats substantially as described.
3. In a Venetian blind, the combination 50 with the slats, slat-suspending straps and the slat-raising roller, of the slat opening and closing rocker-bar, spring for closing the slats and the pull-cord and a pulley-block for actuating the rocker-bar to open the slats, substantially as described.
4. In a Venetian blind, the combination 55 with the slats, slat-suspending straps and the slat-raising roller, of the slat opening and

closing rocker-bar, spring for actuating the rocker-bar to close the slats, pull-cord for actuating the rocker-bar to open the slats, and a counterbalance-weight to hold the slats open substantially as described.

5. The combination with the slat-raising roller, locking-pawls and notched hub, of a pass-over pawl adapted to lodge in the locking-notch and prevent the locking-pawls from locking the roller without slack for jerking the pawls free substantially as described.

6. The combination with the slat-raising roller, locking-pawls and notched hub, of a pass-over pawl adapted to lodge in the locking-notch and prevent the locking-pawls from locking the roller without slack for jerking the pawls free, and means for displacing said pass-over pawl preparatory to locking the roller substantially as described.

7. The combination with the slat-raising roller, locking-pawls and notched hub, of a gravitating pass-over pawl adapted to lodge in the locking-notch and prevent the locking-pawls from locking the roller without slack for jerking the pawls free, and to be displaced by the locking-pawls preparatory to locking the roller substantially as described.

8. In a Venetian blind, the combination with the slats and slat-suspending straps, of a slat opening and closing rocker-bar, and a spring for closing the slats, said rocker having a pull-cord for opening the slats substantially as described.

9. In a Venetian blind, the combination with the slats, slat-suspending straps, slat opening and closing rocker-bar, and the spring for closing the slats of the pulley-block and 95 pull-cord to open the slats, substantially as described.

10. In a Venetian blind, the combination with the slats, slat-suspending straps, slat opening and closing rocker-bar, and the spring 100 for closing the slats, of the crank attached to the rocker-bar, pulley-block connected to the crank, and the pull-cord connected to a hook attached to the window-frame above the crank-arm and passed through said block, and 105 through a guide-eye also attached to the window-frame above the crank-arm all substantially as described.

Signed at New York city, in the county and State of New York, this 17th day of December, 110
A. D. 1896.

PER WALFRID BRUNDIN.

Witnesses:

W. J. MORGAN,
A. P. THAYER.

It is hereby certified that in Letters Patent No. 601,612, granted March 29, 1898, upon the application of Per Walfred Brundin, of New York, N. Y., for an improvement in "Venetian Blinds," errors appear in the printed specification requiring correction, as follows: On page 1, lines 74 and 76, the word "cork" should read *cord*; and that the said Letters Patent should be read with these corrections therein that the same may conform to the record of the case in the Patent Office.

Signed, countersigned, and sealed this 5th day of April, A. D., 1898.
